Primary Examiner — Susan Moon Lee**CLAIM**

The ornamental design for a square pet fountain, as shown and described.

DESCRIPTION

FIG. 1 is a perspective view of the square pet fountain showing my new design;

FIG. 2 is a top perspective view thereof;

FIG. 3 is a front elevation view thereof;

FIG. 4 is a rear elevation view thereof;

FIG. 5 is a left elevation view thereof;

FIG. 6 is a right elevation view thereof; and,

FIG. 7 is a top plan view thereof.

The underside of the fountain is unornamented. The appearance of the underside of the fountain is not claimed.

1 Claim, 5 Drawing Sheets# US D681,887 S
